UNITED STATES PATENT OFFICE.

WILLIAM MATTHES, OF PHILADELPHIA, PENNSYLVANIA.

SCREENING DEVICE.

1,314,826.

Specification of Letters Patent.

Patented Sept. 2, 1919.

Application filed June 3, 1919. Serial No. 301,497.

To all whom it may concern:

Be it known that I, WILLIAM MATTHES, a citizen of the United States, residing at Philadelphia, in the county of Philadelphia and State of Pennsylvania, have invented 5 certain new and useful Improvements in Screening Devices, of which the following is a specification.

One object of my invention is to provide 10 a device which can be easily operated for the purpose of screening material, such for example as for screening or sifting ashes.

Another object is to make my invention 15 of such construction that it can be easily and quickly manipulated to discharge the sifted material and the residue remaining after the sifting action has taken place.

A further object is to make my invention 20 of a strong and durable construction and so that when it is in operation, the material will be retained within a closed space so as to prevent the flying of dust.

These objects, and other advantageous 25 ends which will be described hereinafter, I attain in the following manner, reference being had to the accompanying drawings in which:

Figure 1 is a side elevation of my improved device showing in full lines, the normal 30 position of certain of the elements and in dot-and-dash lines, two tilted positions of said elements,

Fig. 2 is an end elevation of the device shown in Fig. 1,

Fig. 3 is an elevation of the opposite end of the device from that shown in Fig. 2 and illustrating the lid in an open position,

Fig. 4 is a top plan view of the device with the lid open,

Fig. 5 is a central longitudinal section of 40 my improved device showing certain parts of the supporting structure broken away.

Fig. 6 is a front elevation of a rotatable screening cage which forms a part of my invention,

Fig. 7 is a fragmentary sectional elevation 45 showing certain of the elements in an open position, ready to discharge the residue from the screening cage,

Fig. 8 is a fragmentary section taken on the line 8—8 of Fig. 1,

Fig. 9 is a fragmentary section through the screening cage locking means and taken on the line 9—9 of Fig. 2, and

Fig. 10 is a fragmentary plan view partially in section showing a modified form of

means for locking the main housing to the supporting structure.

Referring to the drawings and considering that the device is to be used for sifting 60 or screening ashes, 12 represents a hollow housing which is open at its top and is provided with a lid 13 which is pivoted at 14. The housing 12 has a depression 15 at its bottom which provides a well which has an 65 opening 16 at one end which is normally closed by a slideable door 17.

The housing 12 is pivotally connected at each side, as shown at 18 to a supporting structure which includes two standards 19 70 and 20, said standards being substantially of an inverted V-shape, as clearly shown in Fig. 1. Two guides 21 and 22 are secured to the housing 12 and are positioned at opposite sides of the housing, said guides having slots 23 therein through which the standards 19 and 20 extend. The guides 21 and 22 are arcuate in elevation, the portions adjacent the opposite ends of the housing being of less radius than the intermediate portion, as clearly shown in Fig. 1.

A spring detent in the form of a strip 24 is riveted at 25 to one leg of one of the standards, said detent having a projecting boss 26 adapted to straddle the guide 21 85 when the housing is in its normal position, as clearly shown in Figs. 1, 2 and 8. The detent 24 is provided with a handle 27 by which the detent can be pushed inwardly to free the guide 21 and thereby permit the 90 housing to be swung into either of the dot-and-dash line positions illustrated in Fig. 1.

A screening cage 28 has a shaft 29 secured thereto, said shaft having bearings in the bottoms of two slots 30 and 31 formed in 95 opposite ends of the housing 12, said slots extending downwardly from the top edge of said housing and normally being closed by slideable gates 32, said gates serving to prevent the shaft from moving upwardly in the slots 30 and 31 during the rotation of the screening cage. The shaft 29 has a crank portion 33 provided with a handle 34. The screening cage has a section 35 which is hinged to the body portion 36, and slotted 100 lips 37 are adapted to engage over keepers 38 on the body portion 36. Latches 39 are pivoted to the body portion 36 of the cage 28 and can be swung so as to embrace the keepers and thereby lock the section 35 to 105 the section 36. The end of the body portion 28 of the screening cage has an opening 40

which is normally closed by a door 41 which is hinged at 42 to the body portion 36, said door having a link 43 which is pivoted to a lever 44; the lever being positioned within the screening cage and being pivoted to a bracket 45. The lever 44 has a free end extending in the direction of the pivoted section 35 of the screening cage so that by opening said section 35 it is possible, by moving the lever 44, to open the door 41. The end of the housing adjacent the door 41 has an opening 46 adapted to register with the opening 40 in the screening cage 28. Furthermore, the door 41, when in its open position, extends through the opening 46, as clearly shown in Fig. 7. A door 47 is hinged at its bottom to the housing and normally forms a closure for the opening 46. This door 47 has an angular portion 48 which abuts the end of the housing and retains the door 47 at an angle to said end of the housing and as is also shown in Fig. 7.

The door 47 is provided with side flanges 49 so that the door 47 forms a chute when the housing is tilted, and the residue material will pass out of the opening 40, through the opening 46, and down the chute 49, thereby permitting the discharge of the residue material from the cage. The screened material drops into the well 15 and this screened material can be discharged by opening the door 17 and tilting the housing in the opposite direction.

The screening cage 28 has a strip 50 secured thereto, said strip having an inwardly beveled surface 51 against which the lever 44 presses when the latter lever is moved to close the door 41. When the door 41 is closed, the lever 44 will be positioned against the shoulder 52 and thereby prevents the door 41 from accidentally opening while the screening cage is being rotated. In order to free the lever 44 from the shoulder 52, it is necessary to slightly bend said lever in the direction of its thickness to cause the lever to move away from the shoulder 52 and then slide over the edge surface 51. It will be further noted that when the door 41 is opened, it will extend into the opening 46 and thereby prevent the cylinder from accidentally rotating when the residue is being discharged.

The housing 12 has a rod 53 slidable through one end and this rod has a locking shoe 54 on its inner end adapted to straddle a lug 55 on the screening cage (see Figs. 1, 2, 4 and 9). The upper end of the rod 53 is connected to a plate spring 56, said spring being attached to the end of the housing 12.

A loop 57 consisting of a metallic strip is secured to the housing 12 and a lever 58 which is provided with a handle 59 is pivoted to the housing 12 and extends across the outer surface of the plate spring 56 and

through the loop 57. The plate spring 56 is angularly disposed and normally holds the locking shoe 54 out of engagement with the lug 55 on the screening cage 28. When the lever 58 is moved upwardly it pushes 70 against the spring 56 and causes the rod 53 and locking shoe 54 to be moved inwardly until said locking shoe embraces the lug 55, thereby locking the screening cage against rotation. 75

Considering that my improved device is to be used for sifting ashes from partly burnt coal, the lid 13 is opened as is also the section 35 of the screening cage. The mixed ashes and coal is then inserted within the screening cage and the section 35 is locked and the lid 13 is closed. The lever 58 is then lowered, the spring 56 withdraws the locking shoe 54 from the lug 55. The screening cage is then rotated by means of the handle 34 and the ashes drop into the well 15. The housing is then tilted by pressing the knob 27 inwardly and swinging the housing so that the door 17 moves downwardly. The door 17 is then opened and the ashes 90 will slide out into any suitable receptacle. The door 17 can then be closed and the housing can be swung in the opposite direction, after which the lid 13 and section 35 of the screening cage can be opened so as 95 to actuate the lever 44 to open the door 41, and the door 47 can be dropped to permit the door 41 to extend through the opening in the manner illustrated in Fig. 7. The unburnt coal will then slide through the 100 openings 40 and 46 and the door 47 will serve as a chute for directing the coal into a suitable receptacle.

The door 41 can be closed by moving the lever 44 on its pivot and the strip 50 will cause said lever to be slightly bent until the lever has passed entirely over the strip when said lever will spring back of the shoulder 52 and thereby lock the door 41 in a closed position. The door 47 can then be closed 110 and this door is held in its closed position by a spring keeper 59 which is mounted on the housing 12.

In Fig. 10, I have shown another form of means for locking the housing to the supporting structure. The same consists of a latch 60 which is pivoted at 61 to the guide 22, said latch being movable between the strip 62 and the guide 22, and serving to abut the standard 20. The latch 60 extends 120 across the slot 23 and thereby prevents swinging movement in one direction between the housing and the supporting structure. A similar device can be inserted on the opposite side so as to prevent swinging movement of the housing in an opposite direction. 125

While I have described my invention as taking a particular form, it will be understood that the various parts of my invention 130

tion may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

10 1. A device of the character described including a hollow housing; a screening cage rotatably mounted within said housing; supporting means; means pivotally supporting said housing between its ends whereby 15 the housing can be tilted in opposite directions, said housing including a well positioned below said screening cage and having an opening at one end; a door for closing said opening, said housing having a 20 second opening; a door for closing said second opening; and a door on said screening cage adjacent said latter opening in the housing, whereby material from said screening cage will fall out of said cage and housing when the latter is tilted in one direction and out of said first opening when the housing is tilted in the opposite direction; substantially as described.

2. A device of the character described 30 including a hollow housing; a screening cage rotatably mounted within said housing; supporting means; means pivotally supporting said housing between its ends whereby the housing can be tilted in opposite directions, 35 said housing including a well positioned below said screening cage and having an opening at one end; a door for closing said opening, said housing having a second opening; a door for closing said second opening; 40 a door on said screening cage adjacent said latter opening in the housing, whereby material from said screening cage will fall out of said cage and housing when the latter is tilted in one direction and out of said first opening when the housing is tilted in 45 the opposite direction, said door being hinged to said cage; a link pivotally connected to said door; and a lever connected to said link and to said cage and operative to 50 open said door in registry with said latter opening in the housing; substantially as described.

3. A device of the character described including a hollow housing; a screening cage movably mounted within said housing; 55 means forming a movable support for said housing, said housing including a well positioned below said screening cage and having an opening; a door for closing said opening, said housing having a second opening; 60 a door for closing said second opening; and a door on said screening cage, whereby material from said screening cage can pass out of said cage and housing independently of the material falling into said well, said 65 door in the screening cage being movable into the second mentioned opening in the housing; substantially as described.

4. A device of the character described including a supporting structure; a housing 70 movably mounted on said supporting structure, said housing having an opening and a door for closing said opening; a screening cage movably mounted within said housing and having a door; a pivoted lever connected 75 to said door operative to open and close said door; a strip secured to said screening cage and having a beveled surface; and a shoulder, said lever being movable into engagement with said beveled surface so as 80 to slightly bend the lever and permit it to spring back of said shoulder and thereby lock the door of the screening cage; substantially as described.

5. A device of the character described 85 including a housing; a rotatable member mounted within said housing and having a lug thereon; a plate spring; a rod slid able through said housing and having a shoe for embracing said lug on the rotatable member, said spring normally tending to withdraw said shoe from the lug; and a lever adapted to move said spring and thereby move said shoe into engagement with said lug to lock the rotatable member against 90 movement; substantially as described.

In testimony whereof I have signed my name to this specification in the presence of two subscribing witnesses.

WILLIAM MATTHES.
